UNITED STATES PATENT OFFICE.

JOHN WALTER BRADLEY, OF BRADFORD, ENGLAND.

MACHINE FOR CENTERING AND DRILLING CIRCLES OF MACHINE-COMBS.

SPECIFICATION forming part of Letters Patent No. 550,477, dated November 26, 1895.

Application filed January 4, 1894. Serial No. 495,714. (No model.) Patented in England March 13, 1893, No. 5,346, and in France December 22, 1893, No. 235,011.

To all whom it may concern:

Be it known that I, JOHN WALTER BRADLEY, a subject of the Queen of England, residing at Bradford, England, have invented 5 certain Improvements in Machines for Centering and Drilling Circles of Machine-Combs, (for which I have obtained Letters Patent in Great Britain, No. 5,346, dated March 13, 1893, and in France, No. 235,011, 10 dated December 22, 1893,) of which the following is a specification.

This invention relates to improvements in automatic machinery or apparatus for centering, drilling, and "cutting" or drifting 15 the holes for the pins in circles of Noble's and other machine-combs.

In the accompanying sheets of drawings, forming a part of this specification, similar letters of reference indicate corresponding 20 parts in each of the figures.

Figure 1 is a side view of such parts of a circle-drilling machine as are necessary to illustrate the application of my improvements. Fig. 2 is a front view of the same. 25 Fig. 3 is a plan view of the same. Figs. 4 to 14 are views of details hereinafter referred to. Fig. 15 is a continuation of Fig. 2.

The framework A, face-plate A', on which the circle to be drilled is mounted, and the 30 pawl A² and ratchet A³, connected by change-gearing A⁴ to the worm A⁵, operating the face-plate A', are of ordinary construction. The spindle-head A⁶ is adjustably mounted in the customary manner upon the cross-slide A⁷, 35 mounted upon the gauntlet A⁸; but two spindles B and B' are mounted in this head, one spindle B for drilling in the ordinary way and the other B' for carrying a short stiff drill for "centering"—that is to say, for accurately marking the centers or position of 40 the holes for the drill carried by spindle B to drill. This centering process is not new, but has hitherto been done by a short drill placed in the same spindle as the drill for finishing 45 the hole, and has been done preparatory to the drilling process. Consequently a very considerable saving of time is effected by drilling and centering concurrently.

The centering-spindle B' is mounted in 50 bearings of the usual type for this class of spindle formed in the head A⁶, and the drill-

ing-spindle B is mounted in similar bearings; but these bearings are adjustable in relation to the bearings of spindle B' to allow the alignment of the drilling-spindle in relation 55 to the center-mark made by the centering-spindle to be accurately obtained. For this purpose the drilling-spindle B is mounted in the adjustable portion B⁸ of the head A⁶. This portion B⁸ is mounted in the vertical 60 slide B⁴, Figs. 6 and 7, accurately hinged by the pin B⁵ to the head A⁶. The slide B⁴ provides for the vertical adjustment of the spindle B, and to enable it to be also adjusted at right angles thereto the slide B⁴ is capable of 65 being turned upon the pin B⁵ by the worm B⁶ and hand-wheel B¹², mounted in bearings B⁷ on head A⁶, engaging the segment B⁸, projecting from the back of the slide B⁴, Fig. 8. The bolt B⁹, connected to head A⁶ and passed 70 through the slot B¹⁰ in segment B⁸, Fig. 8, is provided to clamp these parts after adjustment. This is clearly shown in Figs. 4 and 5, which represent a plan and side view of the head and its attachments, and in Figs. 6 and 7, also a plan and side view of the head with 75 parts in section and showing the attachment of certain other parts. Fig. 8 is a view of the right-hand end of Fig. 7. The spindles B and B' are preferably driven by separate belts approximately side by side.

The tail-slide C, for traversing the spindles longitudinally, is mounted upon the two studs C' C', projecting from the rear of head A⁶, and this slide is moved upon such studs by the lever C², Figs. 1 and 2, engaging the plunger-piece C³, fitted in slide C. The two arms of the lever C² are adjustable in relation to each other and are fixed by the bolt C⁴. To allow the position of the head in relation to the stud 85 C⁶, on which such lever is mounted, to be somewhat varied, and in order to enable the stroke of the slide C to be adjusted, the lever C² is connected by a slot to the piece C⁵, and the fulcrum-stud C⁶ is capable of adjustment 90 in the slot C⁶ by the screw C⁷, so that adjusting the stud C⁶ has the effect of altering the length of that arm of the lever operating the plunger-piece C³. The plunger-piece C³ is fitted in a spring-box C⁹, formed in slide C, in 100 which a spiral spring C¹⁰ is placed so as to break the rigidity of the connection between

slide C and lever C², and thus reduce the maximum pressure put upon slide C to that required to compress the spring C¹⁰. The pin C¹¹, fixed in plunger-piece C³ and working in the slot C¹², Fig. 7, prevents the spring pushing piece C³ out of the spring-box, but allows it to be moved independently. The motion of the tail-slide C is communicated to the spindle B through the medium of the worm 5 D, mounted in the arm D', projecting from plunger-piece C³ and adjusted by the hand-wheel D². The worm D engages a rack cut on the side of the spring-box D³, fitted telescopically upon the end of the spindle D⁴, connected by the fork-piece D⁵, Fig. 10, to the spindle B in the ordinary way. To allow of some deviation in the alignment of the spindles B and D⁴ when the slide B⁴, carrying spindle B, is adjusted by the worm B⁶, the end 10 of spindle D⁴, abutting against spindle B, is made somewhat larger, and the arm D⁶ thereon carries a stud D⁷, on which the fork D⁵ is mounted. To clearly show this, a section of the junction of the end of the spindle is shown 15 in Fig. 10. A spiral spring D⁹, Fig. 6, is contained in the spring-box D³, so that the maximum pressure applied to the drill-spindle cannot exceed that required to compress this spring. The lock-nuts D¹⁰, mounted upon the 20 screwed end of spindle D⁴, bear against the end of the spring-box D³ and prevent the spring forcing it off the spindle.

The spindle B' may be operated longitudinally in a similar manner to spindle B; but 25 I prefer to move it more gradually, so as to not feed the centering-drill carried thereby too suddenly against the circle operated upon. With this object the shank of the fork-piece E', (similar to that shown in Fig. 10,) engaging 30 the end of spindle B', is mounted in a slide in tail-slide C, and this slide engages and is operated by the arm E², projecting from the short rocking shaft E³, mounted in bearings formed in tail-slide C, Figs. 6 and 7. 35 The shaft E³ is rocked at each movement of tail-slide C by the arm E⁴, projecting from the end and connected to the fixed stud E⁵ by the short bridle-rod E⁶. As in this arrangement the vibration of the shaft E³ moves 40 arm E² in the reverse direction to that of tail-slide C, but at a slower speed, the movement of the spindle B', operated thereby, is proportionately limited and reduced in speed.

The lever C² is operated to withdraw the 45 tail piece and the drill by the cam F engaging the antifriction-roller F' on the end of said lever, and the spiral spring F², Fig. 1, connected to said lever and fixed at its lower end to the stationary stud F³, is provided to 50 vibrate such lever in the reverse direction to the cam F and feed the drill. The cam F withdraws the drill at each revolution to clear the hole being drilled and to prevent the drill being fed too fast; but to allow it to 55 penetrate a little farther each time it is inserted the antifriction-roller F' also bears upon the comparatively slowly-revolving cam

F⁴ of spiral form. These cams revolve in the direction of the arrow, Fig. 1, and are so relatively operated that the step F⁵ in the 70 cam F⁴ passes the roller F' when the elevated portion of cam F has raised said roller. The cam F⁴ is fixed upon the shaft F⁶, and the cam F is mounted upon the sleeve F⁷, revolving on said shaft, and is driven by the 75 pulley G, fixed thereon, connected by the belt G' to the pulley G² on the main driving-shaft G³. The shaft F⁶ is driven from the sleeve F⁷ by the wheel G⁴, fixed on sleeve F⁷, connected by the stud-wheel G⁵ and the 80 change-wheels G⁶, G⁷, G⁸, and G⁹, mounted upon the stud-plate F⁸, to the wheel F⁹, fixed upon shaft F⁶. The shaft F⁶ is supported at one end by the bracket F¹⁰, and it is also supported by the sleeve F⁷, while the latter 85 is mounted in the standard F¹¹.

To bring the picking mechanism into operation each time a hole is completely drilled, the arm H is provided, pivoted upon the stud H', Figs. 1, 2, and 3, and having a finger H², 90 Fig. 2, resting upon the adjustable sleeve D¹¹, mounted upon the spindle D⁴, projecting from the spring-box D³, Fig. 3. The arm H is so arranged that its free end is capable of a limited downward movement, so that when the 95 drill passes through the circle the finger H² drops off the end of sleeve D¹¹, Fig. 3. This allows a spacing-piece H³, Fig. 1, carried by arm H, to pass between the rapidly-revolving cam H⁴ and the end of the rod H⁵, Figs. 1, 2, 100 and 3, normally held in the position shown by the spring H⁶, but capable of a certain amount of longitudinal motion, and this longitudinal motion is imparted to it each time the spacing-piece H³ passes between it and 105 the cam H⁴. The rod H⁵ has an inclined face H⁷ at its opposite end, and this inclined face bears against the projection H⁸ on the spring-detent H⁹, holding the lever J, Figs. 3 and 4. When the rod H⁵ is moved longitudinally, its 110 inclined face engages the projection H⁸, and thereby retracts the pivoted detent from in front of the lever J, Fig. 1, allowing the latter to move forward.

The detent, from Figs. 1, 3, 4, and 5, it will 115 be observed, is pivoted centrally and moves in a horizontal plane. In its normal position its free end projects in front of the upper end of the lever J and holds the latter retracted; but when the rod H⁵ is moved in by the cam 120 through the interposition of the spacing-piece the incline on the rod pressing against the forward end of the detent, or more properly against the projection H⁸ on the forward end of the detent, operates it, as described. This 125 lever is mounted upon a stud F¹², fixed to the top of the bracket F¹³, projecting from head A⁶, and is connected by the connecting-rod J' to the lever J³ on the picking-shaft J⁴, supported in bearings J⁵, fixed to the gauntlet A⁸, 130 and this picking-shaft J⁴ is connected by the arm J⁶ and link J⁷ to the pawl A² of the ratchet picking motion. A spring J⁸, inclosed in a spring-box J⁹ on the shaft J⁴, Fig. 3, is coiled

round said shaft and is so arranged that as soon as lever J is released the picking-shaft, moving under the influence of such spring, turns sufficiently to bring the pawl A² onto the next tooth of the ratchet A³ and at the same time draws the lever J toward it. The lever J has an arm K connected by a link to the arm K' on the rocking shaft K², Fig. 1, mounted in bearings f in the casting F¹³ F¹¹, and when the lever J is moved in the above-described manner this shaft is also partly turned. The shaft K² has an arm K³, Figs. 11, 12, and 13, fixed to its opposite end, carrying a spring-stud K⁴, and when the shaft K² is moved the said stud bears upon the incline K⁵, carried by the bracket K⁶ on casting F¹¹, and such stud is moved longitudinally, so that the antifriction-roller K⁷ on the end thereof is moved into the same plane as and within reach of the cam K⁸, mounted upon the sleeve F⁷. This is shown in detail in Figs. 11, 12, and 13, as well as in Figs. 2 and 3. The anti-friction-roller is only held in this position until the rise of the cam K⁸ engages it, and by vibrating the arm K³ turns the shaft K², and through the medium of the connecting mechanism restores the lever J to its normal position, where the detent H⁹ retains it, and at the same time rocking the picking-shaft J⁴, so as to turn the picking mechanism the distance of one tooth of the ratchet and thereby move the circle into position for the next hole to be drilled and centered. As soon as the cam K⁸ has effected this movement, a reduced portion or depression in its periphery allows the spring-stud to spring back to the position shown in the drawings, thus moving the anti-friction-roller out of the path of the cam, where it remains until the hole is drilled.

For very delicate drilling a sliding piece L, carrying the drill-chuck, is accurately fitted in the adjustable screw-plug L', fitting a female screw-thread in the hollow nose of the spindle B, as shown in Figs. 6 and 7. This sliding piece is free to move inward, but is made to rotate with the plug by a pin L², fixed in plug L' and passing through the slot L³ in sliding piece L. A light spiral spring L⁴ is placed in the hollow nose of the spindle to press sliding piece L to its normal limit, so that the maximum feed-pressure on the drill cannot exceed the pressure required to compress this spring, and this pressure may be regulated by screwing plug L' in or out. If this spindle is used for work too heavy for the spring L⁴, a second pin, similar to pin L², is passed through the slot L³, but at the opposite end, so as to prevent the sliding piece L being pressed inward.

When the sliding piece L is in use, I employ a modified arrangement (shown in Figs. 4 and 5) to bring the picking mechanism into operation. In this case the finger H¹² rests upon the nose of the spindle and is fixed upon the light shaft M, mounted in bearings M', supported by bracket F¹³ and head A⁶, and the spacing-piece H³¹, corresponding exactly

to the spacing-piece H³ in the other figures, is fixed on the other end of this shaft. An annular groove M³ is formed in the sliding piece L on the spindle, and the parts are so arranged that when each hole is completed the finger H¹² drops into such groove, thereby slightly turning the shaft M and thus introducing the spacing-piece H³¹ between the cam H⁴ and the end of the rod H⁵. With the exception of the light shaft M and the means for moving it with the spacing-piece the parts are the same and bear the same relation to each other as in the other figures, and, as in the other figures, thus referring to these figures as well as to Figs. 1, 2, and 3, the cam H⁴ is mounted on a short shaft M³, mounted in the bracket M⁴, connected to bracket F¹³, and this shaft is rapidly rotated by the band M⁵, communicating motion from the pulley M⁶ on the driving-shaft G³ to the pulley M⁷ on shaft M³.

To lift the spacing-piece in both forms of device from between the cam H⁴ and the rod H⁵, a second cam N is mounted upon shaft M³, which engages the arm N', (lettered N¹¹ in Figs. 4 and 5,) connected rigidly with the spacing-piece, and at each revolution lifts the spacing-piece into its normal position until the spindle B is withdrawn and finger H¹² is clear of the groove M³.

Fig. 9 is a separate view of the cam-shaft M³ and certain other parts.

When the finger H² is carried by the arm H, as described above with reference to Figs. 1, 2, and 3, the second cam N, Fig. 3, is also employed, as before stated, to lift arm H by engaging the finger N', Fig. 2.

A separate drifting or cutting head is preferably employed, mounted at the other side of the machine and adapted to carry two or more drifts or cutters capable of delicate adjustment in relation to each other. The spindle or spindles of the cutting-head is or are moved longitudinally by a cam motion arranged to quickly withdraw the cutters, and such cam may be driven by different mechanism and at a greater speed to that operating the drilling-cam.

The same "picking" motion may be employed for the drifting or cutting head; but it is in this case operated at each motion of the drifting-spindle after the cutters are withdrawn.

The drifting or cutting-head O mounted on the gauntee A⁸, as shown in Figs. 3 and 15 and a separate side view in Fig. 14, is provided with a spindle O', of square or other suitable section, fitted in bearings in said head so that it is free to slide to and fro longitudinally. This spindle is adapted to carry two drifts or cutters fixed in the chucks or holders O² O², mounted upon the vertical slides O³ O⁴, and adjusted by the screws O⁴ O⁴. The slides O³ O⁴ are formed on the horizontal sliding piece O⁵ O⁶, (adjusted by the screws O⁶ O⁶), fitting in guides O⁷ O⁷, secured to the end of the spindle O'. The opposite end of the

spindle O' carries an antifriction-roller P, bearing against the cam P', which is arranged as it rotates to press the spindle O' inward to pass the drifts through the holes, and a spiral 5 spring O⁸, inclosed in a spring-box and surrounding the spindle, bears against the collar O⁹ on the spindle, and moves the spindle in the reverse direction to the cam to withdraw the drifts. After the drifts are withdrawn 10 the cam P' is so formed that they remain in that position until the picking motion is brought into operation and the pick made as now described.

The cam P' is mounted upon the shaft P², 15 revolving in bearings P³, connected to the head O, and such shaft is driven by the band P⁴, connecting the pulley P⁶ on the main shaft G³ to the pulley P⁵ on shaft P². The shaft P², Fig. 3, also carries a crank-disk P⁷, the 20 crank-pin P⁸ of which is connected by the rod P⁹ to the arm P¹⁰ of the picking-shaft J⁴, and by this means the picking motion is brought into operation at each movement of the spindle O'.

25 The length of the rod P⁹ is adjustable to allow the head O to be moved inward or outward. The crank-pin P⁸ is fitted in a sliding block R, fitting a slot in the end of the rod, and a spring R', the pressure of which is regulated by the screw R³ bearing upon said block. The spring R' is confined between the end of the slot and the nut R³ of the screw, so that the screw which freely passes through a hole in the end of the slot tends under the 30 influence of the spring to keep the block R at the opposite end of the slot; but nevertheless in case of abnormal pressure the block is free to move in the slot.

Having now particularly described and ascertained the nature of my said invention and 40 in what manner the same is to be performed, I declare that what I claim is—

1. In a drilling machine, the combination with a reciprocating tail piece with mechanism for reciprocating the same, of two parallel drill spindles moved simultaneously toward and from the work by said tail piece and a feed mechanism for feeding the work a distance corresponding to the distance between the drills, whereby the holes may be 45 centered by the tool carried by one spindle and drilled by the tool carried by the other spindle; substantially as described.

2. In a drilling machine, the combination with the reciprocating tail piece, of two parallel spindles moved longitudinally by said tail piece and a spring interposed in the connection between the tail piece and one of the spindles; substantially as described.

60 3. In a drilling machine, the combination with the reciprocating tail piece, of two spindles moved longitudinally by said tail piece and a speed reducing mechanism interposed in the connection between the tail piece and one spindle whereby one spindle is advanced more rapidly than the other; substantially 65 as described.

4. In a drilling machine, the combination with the reciprocating spindles and a mechanism for reciprocating both of the same, of a speed reducer interposed in the operating connections of one spindle; substantially as described. 70

5. In a drilling machine, the combination with the reciprocating spindles and cross-head or tail piece for advancing both spindles, of a lever pivoted on the tail piece and having one arm cooperating with the spindle slide and another and longer arm cooperating with a fixed bearing whereby the speed 75 of the spindle is reduced; substantially as described.

6. In a drilling machine, the combination with the two reciprocating spindles and a tail piece for simultaneously advancing the 80 spindles, of adjustable bearings for one spindle and a loose connection interposed between said spindle and tail piece whereby the adjustment of the spindle does not break its operating connection with the tail piece; substantially as described. 85

7. In a drilling machine, the combination with the centering spindle, of the boring spindle, a vertically movable carriage in which 90 said boring spindle is journaled, a pivoted block having ways for said carriage, and adjusting mechanism for the carriage and block; substantially as described. 95

8. In a drilling machine, the combination with a reciprocating tail stock, and a centering spindle moved longitudinally thereby, of a boring spindle also moved longitudinally by said tail stock and mounted in bearings held in parallelism with the centering spindle and adjustable in a vertical and a horizontal direction with relation to said centering spindle; substantially as described. 100

9. In a drilling machine, the combination with a reciprocating tail piece, of a spindle mounted in adjustable bearings, and a pivoted fork and stud forming the connection between the tail piece and spindle, whereby the adjustment of the spindle does not break the operative connection with the tail piece; substantially as described. 110

10. In a drilling machine, the combination with the longitudinally movable spindle and a controlling finger released by the movement of the spindle, of a picking mechanism, a rotary cam controlling the same and a spacer 115 operated by the controlling finger for throwing the cam into operative connection; substantially as described.

11. In a drilling machine, the combination with the longitudinally movable spindle and a controlling finger released by the movement of the spindle, of a picking mechanism, a detent for holding the same in check, a revolving cam for throwing the detent out of operation and a spacer moved by the controlling 120 finger for throwing the cam into operative connection with the detent; substantially as described. 125

12. In a drilling machine the combination

with the drilling spindle and means for advancing the same, of a rapidly moving cam for retracting said spindle and a slowly moving cam forming a gage for regulating the 5 depth of the cut at each reciprocation, and gearing for moving said cams; substantially as described.

13. In a drilling machine, the combination with the drilling spindle and means for advancing the same, of the cam for withdrawing the spindle, the cam forming a gage to regulate the depth of the cut at each reciprocation and change gearing interposed between the cams whereby a differential speed 15 is imparted to the cams; substantially as described.

14. In a drilling machine, the combination with the drilling spindle and means for advancing the same and a picking mechanism 20 controlled by the spindle, of the slowly moving cam for gaging the depth of the cut, the

rapidly moving cam for withdrawing the spindle a number of times during the boring of each hole and a picker operating cam moving in unison with the withdrawing cam; sub- 25 substantially as described.

15. In a drilling machine, the combination with the reciprocating spindle and a rotary picker cam, of a picker, a detent controlled by the spindle for holding the picker in check 30 and a spring for moving the picker into position to be operated by the cam when released by the movement of the spindle; substantially as described.

In testimony whereof I have hereunto set 35 my hand in the presence of the two subscribing witnesses.

JOHN WALTER BRADLEY.
